US0D1046636S

(12) **United States Design Patent** (10) Patent No.: **US D1,046,636 S**
(45) Date of Patent: ** Oct. 15, 2024

(54) **THERMOSTAT**

(71) Applicant: **SmartRent Technologies, Inc.**,
Scottsdale, AZ (US)

(72) Inventors: **Isaiah DeRose-Wilson**, Scottsdale, AZ
(US); **Douglas Tarlow**, Scottsdale, AZ
(US); **Sebastian Popovic**, Zagreb (HR);
Tomislav Sečen, Zagreb (HR)

(73) Assignee: **SmartRent Technologies, Inc.**,
Scottsdale, AZ (US)

(**) Term: **15 Years**

(21) Appl. No.: **29/855,571**

(22) Filed: **Oct. 4, 2022**

(51) LOC (14) Cl. **10-05**

(52) U.S. Cl.

USPC **D10/50**

(58) **Field of Classification Search**

USPC D10/4, 15, 40, 50, 52, 53, 49; D13/162,
D13/164, 168

CPC F24F 2110/10; F24F 11/52; F24F 11/523

See application file for complete search history.

(57) **CLAIM**

The ornamental design for a thermostat, as shown and described.

DESCRIPTION

FIG. 1 illustrates a perspective view of a thermostat;
FIG. 2 illustrates a top view of the thermostat of FIG. 1;
FIG. 3 illustrates a bottom view of the thermostat of FIG. 1;
FIG. 4 illustrates a front view of the thermostat of FIG. 1;
FIG. 5 illustrates a back view of the thermostat of FIG. 1;
FIG. 6 illustrates a left side view of a thermostat of FIG. 1;
and,
FIG. 7 illustrates a right side view of a thermostat of FIG. 1.
The broken lines in the figures are included for the purpose of illustrating portions of the thermostat and form no part of the claimed design.

1 Claim, 5 Drawing Sheets
